his Attorney.

UNITED STATES PATENT OFFICE.

MARIUS JEAN-BAPTISTE BARBAROU, OF PARIS, FRANCE.

ENGINE-TURNING GEAR.

Application filed May 21, 1923. Serial No. 640,460.

To all whom it may concern:

Be it known that I, MARIUS JEAN-BAPTISTE BARBAROU, citizen of the French Republic, residing at Paris, in the French Republic, have invented new and useful Improvements in Engine-Turning Gears, of which the following is a specification.

The present invention has for its object an engine turning gear i. e. a device for operatively connecting a motor with an auxiliary motor or starter, in order to avoid, at the time of engagement of the gear wheel connected to the crankshaft of the motor with the pinion of the starter, the violent shocks which might injure these parts.

The engine turning gear according to the invention comprises a spring which transmits the movement of rotation of the starter to a nut which is combined with a screw secured to the driving pinion, the rotation of the nut causing a very slow rotation of said screw and said pinion and a translation of the latter at a reduced speed for engaging it with the gear wheel mounted on the crankshaft of the engine.

Other characteristic features of the invention will appear from the following description.

The appended drawing shows in longitudinal axial section, and by way of example, a form of construction of the device according to the invention.

As shown in the drawing, A is the shaft of the starter, which in the case of an electric starter is the shaft of the armature. To the shaft A is keyed a bell-shaped piece B. Within the said piece B, a sleeve E, to which is secured a disc C, is slidable with easy friction.

The sleeve E is driven by the piece B through the medium of the coil spring R. This spring by reason of the rotation of the piece B, tends to become wound on the one hand upon the said piece B, and on the other hand upon the piece C. This winding produces an energetic tightening which causes the rotation of the sleeve E. The spring is so disposed that it acts only by winding and not by lengthwise tension. It should be observed that the sleeve E may assume a lengthwise movement within the piece B, said translation being stopped by a washer B' which is clamped between the piece B and the nut securing the latter upon the shaft A of the armature of the starter.

The inner wall of the sleeve E is screw-

threaded, and a screw H is screwed within said sleeve. This screw H, on the other hand, is adapted to drive the pinion F. The centering of said pinion F is ensured on the one hand by the threads of the nut E, and on the other hand by the ball bearing T. G is the gear wheel mounted on the engine crankshaft, and S a spring which tends to hold the nut H in the position of rest.

The operation of the device is as follows: When the starter is set working, its shaft A rotates and drives the sleeve or nut E through the medium of the piece B and the spring R. But the screw H, by reason of its inertia, assumes a movement of rotation which is much slower than the rotation of the nut E, thus producing a lengthwise movement of this screw H, which pushes the pinion F into gear engagement with the flywheel G mounted on the crankshaft of the engine.

In the case in which the tooth of the pinion should not be opposite a recess of the toothed part of the flywheel, the pinion will be stopped in its translation, but the resulting shock is damped by the fact that the piece E and hence the pieces secured thereto may move backward by bearing against the spring R. This translation speed is also reduced by the inertia which tends to produce a slight back motion of E. The rotation may thus proceed on, and as soon as the opposite toothed parts are in the proper position, the engagement will take place.

When the internal combustion engine to be started is in motion, it tends to rotate the pinion F at a greater speed than that due to the action of the electric (or other) motor of the starter. By reason of this differential motion, the piece H becomes screwed into the nut E, and the pinion F is then released from the teeth of the flywheel G and returns to the position of rest, which position is stabilized by the action of the spring S.

It should be remarked that the pinion F is designed so as to be independent of the screw H so that it may be readily replaced and this will thus limit the placing of the starter in the proper working conditions, to the replacing of a piece which is of a simple inexpensive construction.

Various constructional modifications may be obviously made in the device described

without for this reason departing from the invention.

Having now described my invention, what I claim as new and desire to secure by 5 Letters Patent is:

In combination with the crankshaft of an engine and the shaft of a starter for said engine, a gear comprising a toothed wheel, means for operatively connecting said 10 toothed wheel to said crankshaft, a bell shaped member mounted on the end of said shaft of the starter, a nut carried and adapted to slide within said bell shaped

member, a stop piece for stopping the sliding movement of said nut, a coil spring surrounding said nut and attached to said bell shaped member and to said nut respectively, a screw cooperating with said nut and carrying a pinion adapted to engage with said toothed wheel and yielding means for normally maintaining said screw and nut in their inoperative position.

In testimony whereof I have signed my name to this specification.

MARIUS JEAN-BAPTISTE BARBAROU.
